UNITED STATES PATENT OFFICE.

ELMER E. VAN WIE, OF LOS ANGELES, CALIFORNIA.

BUILDING CONSTRUCTION.

Application filed September 24, 1923. Serial No. 664,401.

To all whom it may concern:

Be it known that I, ELMER E. VAN WIE, a citizen of the United States, residing at Los Angeles, in the county of Los Angeles and State of California, have invented a certain new and useful Improvement in Building Constructions, of which the following is a full, clear, and exact description, reference being had to the accompanying drawings.

This invention relates to building blocks or tile which are adapted to be arranged to form a wall or other building structure.

The general object of the invention is to provide an improved type of building block adapted for use in the building art and wherein the units or blocks are of such a character that they can be quickly and easily manufactured and assembled.

One of the specific objects of the invention is to provide a wall composed of a plurality of similar units so constructed that they may be interlocked during assembly, after which they may be united into a monolithic structure.

Another object of the invention is to provide a building block which is composed partially of wood and partially of cementitious material so arranged that when a number of blocks are assembled together in a wall, the wooden portions form a continuous insulating strip.

An additional object of the invention is to provide a building structure made of units comprising front and back members united by fastening elements and so constructed that the fastening members serve in the completed structure to form reenforcement for cementitious material.

Further objects of the invention will be apparent from the following description taken in connection with the accompanying drawings wherein Fig. 1 is a fragmentary perspective view of a building structure embodying the features of my invention; Fig. 2 is a section on line 2—2, Fig. 1; Fig. 3 is a perspective detail showing a jamb block embodying the features of my inven-

tion; Fig. 4 is a section on line 4—4, Fig. 3; Fig. 5 is a perspective view of one of the building units; Fig. 6 is a section on line 6—6, Fig. 5; Fig. 7 is a perspective view of a corner block; Fig. 8 is a section on line 8—8, Fig. 7; Fig. 9 is a fragmentary perspective view showing my invention embodied in a floor or roof structure; Fig. 10 is a plan of a full length block; Fig. 11 is a section on line 11—11, Fig. 10; Fig. 12 is a plan of a half block; Fig. 13 is a section on line 13—13, Fig. 12; Fig. 14 is a sectional view through a modified form of block; Fig. 15 is a perspective view of a curved structure such as a silo embodying the features of my invention; Fig. 16 is a top plan view of the silo; Fig. 17 is a plan of one of the units used in constructing the silo; Fig. 18 is a section on line 18—18, Fig. 17; Fig. 19 is a plan view of a silo jamb block; Fig. 20 is a section on line 20—20, Fig. 19, and Fig. 21 is a section of a tile taken through the fastening members.

Referring to the drawings by reference characters, I have shown at 10 a wall embodying the features of my invention. As illustrated, the wall is composed of a plurality of tiles or blocks in which the main body of the wall is composed of a plurality of similar blocks 11. These blocks, as shown, comprise front and back members 12 and 14 and a pair of end members 15 and 16. As illustrated, the front and back members are rectangular and have plane front and back faces. The end members 15 and 16 likewise have plane front and back faces.

The end members have their inner ends 17 and 18 disposed in substantially the same plane as the plane of the ends 19 and 20 of the front and back. The end members 15 and 16 are secured to the front and back by fastening members 21. Each of these fastening members comprises preferably a metallic strip having one end secured in the front or back and having the other end secured in the end members.

I now find that the most economical construction is to make the end members 15 and

16 of wood and to construct the front and back members of cementitious material such as concrete. The fastening members 21 may merely be nails or spikes driven into the end members 15 and 16.

In constructing the units I first insert the fastening members or nails in the end members 15 and 16. After this, the front 12 may be cast so that the heads of the nails 10 will be embedded therein. After the front has cured the partially formed block may be turned over and the back 14 may be formed. If desired, the front 12 may have a surface 22 thereon which may be made to simulate 15 marble or other material as desired.

The blocks shown at 11 are used in building the sides of the wall. When the use of a jamb block is required, I prefer to use the one illustrated in Fig. 3 wherein the block 20 comprises front and back portions 25 and 26 as shown in Figs. 3 and 4. The interlocking members for the jamb block are shown at 27 and 28. It will be noted that the inner end of the locking block 27 is in the same 25 plane as the plane of the ends of the blocks 25 and 26. The block 28 is arranged with its outer face in the same plane as the plane of the outer faces of the ends of the blocks 25 and 26. The front and back of the jamb 30 block are united by members 29 which are arranged and secured in a manner similar to that of the members 21 previously described. The use of one of the jamb blocks embodying the features described is shown 35 at A, Fig. 2 of the drawing.

A corner block embodying the features of my invention is shown at 30 in Figs. 7 and 8. This block preferably includes an angle member 31 and a pair of locking members 40 32 and 33 which are joined by fastening members 34. The inner faces of the blocks 32 and 33 are preferably arranged in the same plane as the plane of the ends of the angle member 31.

The fastening members 34 which unite the 45 portions of the corner block as well as the fastening members 29 which serve to unite the portions of the jamb block are preferably of the same character as the fastening member 21 previously described and they are 50 preferably spaced from the top and bottom of the jamb block and corner block in the same manner as described for the fastening members 21.

Referring to Fig. 9, I here show the use of 55 my invention as applied to the floor or ceiling of a building structure. Instead of laying the blocks with the front and back faces 12 and 14 in a vertical plane I lay these 60 blocks with their faces horizontal and with their interlocking portions 15 and 16 interlocking in the manner previously described.

Suitable reenforcing means may be provided in any of the structures and as illustrated in Fig. 9 such reenforcement may be

a metal rod 38 which is spaced between the insulating members 15—16 and the outer portion 14. The cementitious material such as concrete may be inserted in the space between the center member and the portions 12 70 and 14 by using a cement gun which is well known in the art.

Referring to Figs. 10 and 11, I here show a block which is adapted to be used as a full unit in constructing my wall while in 75 Figs. 12 and 13 I show a half-block. In Fig. 13 it will be noted that in order to provide reenforcement for the front and back members, I indicate a wire 40 wrapped about the ends of the fastening members 21. It 80 will be noted from Fig. 13 that the front 12' of the block is made of a single piece of material instead of two united layers as shown in Fig. 5.

In Fig. 14 I show a modified form of my 85 invention wherein a block similar to the block previously described is illustrated. This block comprises a front and back 12^a and 14^a and end members 15^a and 16^a. A fastening member for uniting the front and 90 back to the ends is shown as a metal hoop 41 which is cast into the front and back 12^a and 14^a and which passes through apertures in the end members 15^a and 16^a. As an added 95 reenforcement, I may coil a wire 45 about the portion of the hoop 41 which is embedded in the front and back 12^a and 14^a.

My invention is particularly adapted for the building of silos particularly an account 100 of the ease of manufacturing the various units and the fact that the insulating members may be made of waste lumber and also on account of the fact that the device is very economical and can be easily erected by unskilled labor. An illustration of my invention embodied in a silo is shown in Figs. 15 105 and 16. The silo here shown is made of a plurality of interlocking tiles comprising whole units and half units which are shown in detail in Figs. 17 and 18. I prefer to construct the front and back 50 and 51 of each unit with curved front faces although planar faces may be used in building a silo, if desired. The end members 52 and 53 are 110 preferably plane on both front and back and are united to the front and back by fastening members 54 in a manner previously described so that the units can be placed one upon the other.

Referring to Figs. 19 and 20, I here show 115 a jamb block for use in a silo. This block is similar to the jamb block shown in Fig. 4 and comprises front and back members 55 and 56 and locking members 57 and 58 secured to the front and back by fastening members 59.

In the manufacture of tile such as described, I may construct the front and back members of plaster, cement, clay, or other material although I prefer material which 120

- may be molded. I may construct the interlocking members of wood or of cement, clay or other material. The fastening members may be spikes, bolts, wire or other means.
- 5 The simplicity of my invention allows a wide choice of materials to be made while at the same time the cost of manufacture will be low.
- Having thus described my invention, I claim:
- 10 1. A building tile adapted to be placed in a wall, said tile comprising separately formed front and back portions and separately formed interlocking members arranged intermediate the front and back portions and secured thereto, said interlocking members projecting beyond the front and back portions at each end of the tile.
- 15 2. A wall comprising a structure made from a plurality of tiles, each tile comprising independent front and back members joined to an independent intermediate member, said front, back and intermediate members being spaced apart, a plurality of fastening members secured to the intermediate members, said fastening members being angularly arranged with respect to the front and back members and secured to the front and back members, said fastening members
- 20 serving to hold said front, back and intermediate members in spaced relation and to interlock said members in the wall.
- 25 3. A building tile adapted to be placed in a wall, said tile comprising two rectangular planar portions constituting the front and the back of the tile, a pair of interlocking members secured to said front and back and spaced from said front and back, said interlocking members being spaced apart laterally.
- 30 4. A wall constructed from unitary blocks, each block comprising front and back members formed of cementitious material, interlocking members on each end of each block, said interlocking members having plane parallel faces and being spaced from the inside of said front and back members, and a filling of cementitious material between said interlocking members and the front and back members, the interlocking members in each unit being spaced apart laterally.
- 35 5. A wall comprising a plurality of units each including pre-cast front and back members, interlocking connecting members secured to the sides of said front and back members and laterally arranged with respect thereto, said connecting members having their front and back faces in substantially parallel planes and forming a substantially continuous strip and a filling of cementitious material between the connecting members and the front and back members.
- 40 6. A building tile adapted to be placed in a wall, said tile comprising two rectangular portions constituting the front and the back of the tile, an end member projecting beyond each end of said front and back and having plane parallel front and back faces and connected thereto by means spaced from the top of the front and back, said end members being of less thickness than the space between the front and back.
- 45 7. A building tile adapted to be placed in a wall and comprising a rectangular portion constituting the front of the tile and a pair of end members, one disposed at each side of said front and connected thereto by means spaced from the top of the front, the total width of the end members being substantially equal to the width of the front, said end members having their inner faces in substantially the same plane as the plane of the ends of the front portion.
- 50 8. A building tile adapted to be placed in a wall and comprising four members, the front and back of each member being plane and having all members positioned in parallel planes spaced apart, the end of said members being plane, the outer ends of certain of said members being in the same plane as the inner ends of other members and means to hold all the members in the said relation.
- 55 9. A building tile adapted to be placed in a wall and comprising two rectangular portions constituting the front and the back of the tile, a pair of end members, one disposed at each side of said front and back and connected thereto by means spaced from the top of the front and back, the total width of the two end members being substantially equal to the width of the front and back, said end members having their inner faces in substantially the same plane as the plane of the ends of the front and back members.
- 60 10. A building tile comprising two portions constituting the front and the back of the tile, a pair of end members, one disposed at each side of said front and back members and connected to those members by reinforcing means spaced from the top and bottom of the tile, said end members having their inner faces in substantially the same plane as the plane of the ends of the front and back members, said reinforcing means being adapted to coact to support the front and back when the parts are assembled.
- 65 11. A wall constructed from a plurality of tiles, each of said tiles comprising two rectangular members constituting the front and the back, and a pair of ends, one disposed at each side of said front and back members and connected to those members by means spaced from the top and bottom of the tile, the total width of said ends being substantially equal to the width of the front or back, said connecting means being adapted to coact to support the front and back when the parts are assembled, said ends

forming a continuous strip spaced from the front and back and a filling of cementitious material between said ends, and the inner surface of the front and back members.

5 12. A wall built of a plurality of similar units, each unit comprising a body portion having parallel front and back members and parallel end members, means connecting

the front and back and the end members, said means being spaced from the ends of all 10 the members whereby a plurality of notches are formed, the notches of adjacent units being interlocked.

In testimony whereof, I hereunto affix my signature.

ELMER E. VAN WIE.
